US0D1097224S

(12) **United States Design Patent** (10) Patent No.: **US D1,097,224 S**
(45) Date of Patent: ** Oct. 7, 2025

(54) **FOG LIGHT**

(71) Applicant: **Guangzhou Chengguang Future Automotive Lighting Co., Ltd., Guangzhou (CN)**

(72) Inventor: **Lanyan Jiang, Guangzhou (CN)**

(73) Assignee: **Guangzhou Chengguang Future Automotive Lighting Co., Ltd., Guangzhou (CN)**

(**) Term: **15 Years**

(21) Appl. No.: **29/823,999**

(22) Filed: **Jan. 21, 2022**

(30) **Foreign Application Priority Data**

Jan. 13, 2022 (CN) 202230020110.X

(51) **LOC (15) Cl.** **26-06**

(52) **U.S. Cl.**

Primary Examiner — George J Ulsh

Assistant Examiner — Kathryn Elizabeth Chambers

(57) **CLAIM**

The ornamental design for a fog light, as shown and described.

DESCRIPTION

FIG. 1 is a first perspective view of a fog light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the fog light that form no part of the claimed design.

1 Claim, 8 Drawing Sheets
